[57] CLAIM

The ornamental design for an anchoring plate for dental posts, as shown and described.

DESCRIPTION

FIG. 1 is a bottom plan view of an anchoring plate for dental posts showing my new design;

FIG. 2 is a top plan view thereof;

FIG. 3 is a front elevational view thereof;

FIG. 4 is a rear elevational view thereof;

FIG. 5 is a cross-sectional view thereof;

FIG. 6 is a left side elevational view thereof, the right side being a mirror image.

FIG.1

FIG.2

FIG. 3

FIG. 4

FIG. 5

FIG. 6
